OF TOLEDO, OHIO

PAVEMENT CONSTRUCTION

Application filed October 24, 1930. Serial No. 490,927.

My invention has for its object to provide a pavement construction that is particularly of value when used in connection with railroad crossings where the pavement is not only subject to the wear and tear of heavy traffic, but also where repair of the railroad bed for readjustment of the bed or rails is constantly required in order to maintain the rails in proper alignment with the adjoining portions of the track. The invention thus provides a pavement that will withstand the wear of traffic and is readily removable and replaceable in order that the railroad bed may be reformed or repaired.

The invention also provides a pavement construction formed of parts that are electrically insulated from each other to prevent short circuit between the rails where the rails form parts of a signalling or indicator system. The invention also provides an elastic, slightly yieldable structure that prevents breaking of the parts that form the pavement.

The invention may be contained in pavement or floor constructions usable for a great variety of purposes and, to illustrate a practical application of the invention, I have selected a cross-rail roadway construction having elements or members formed of cast wrought iron and interlocking and insulating parts so formed that the roadway or pavement may be readily removed and replaced as may be desired.

The particular construction selected as an embodiment of my invention is shown in the accompanying drawings and is described hereinafter.

Fig. 1 is a perspective view of the portion of the pavement located between the rails of a railroad. Fig. 2 is a view of a section taken on a plane located at right angles to the rails. Fig. 3 is a view of a section taken on the plane of the line 3—3 indicated in Fig. 2. Fig. 4 is a view of a section taken on the plane of the line 4—4 indicated in Fig. 2. Fig. 5 is a view of a section taken on the plane of the line 5—5 indicated in Fig. 3.

In the particular form of inter-rail pavement construction shown in the drawings, a plurality of slabs or members, each formed

preferably of a plurality of electrically insulated sections, are disposed between the rails and are so located one relative to the other that they form a surface preferably located substantially at the level of the tops of the rails, or slightly below the level of the tops of the rails, and a channel to enable the flanges of the railroad engine and car wheels to move over the rails. The rails 1 are secured to suitable ties 2, which are embedded in the track-bed. The rails 1 are secured by the usual spikes 3 to the ties 2. A plurality of cast iron slabs, or members, 5 are provided with a plurality of lugs or short flanges 6 and 7 that extend from opposite side edges of the member 5. The lugs or flanges 7 are located below the planes of the lugs or flanges 6 and preferably so that the top surfaces of the flanges 7 and the under surfaces of the flanges 6 will lie in the same plane. The flanges or lugs are spaced apart about the width of the flanges. One end of each slab or member 5 has a pair of flange portions 7 on opposite side edges and the other end of the slab or member 5 has a pair of flange portions 6 on opposite sides of the slab 5. The slabs are so positioned between the rails that the ends of the slabs having the flanged portions 6, located along one of the rails, alternate with the ends of the slabs having the flanged portions 7. Thus the arrangement is such that the slabs may be placed together and the flanges, which are of equal length, will lie one above the other, or overlap. When the members are secured from movement along the tracks, they will interlock, due to the dove-tailing of the flanges.

The opposite ends of the slabs are provided with downwardly extending portions that are so formed that, when they rest upon the bases 10 of each of the rails, they will support the tops of the slabs substantially in the plane of the rails. One end of each slab is provided with a downwardly extending portion 11, that substantially fills the space between the base 10 of the rail and the underside of the top 12 of the rail. The opposite end of each slab has a downwardly extending part 14. The portion 11 fits in this space and is held in this position when the other end of

the slab is placed so that the downwardly extending part 14 is placed upon the base of the other rail. The downwardly extending part 14 of each of the slabs substantially 5 conforms to the portion 11 to form the channel 9 along each rail. The part 14, however, has a sufficient clearance between its end and the rail 1 to permit the portion 11 to be placed in position on one of the rails and the other 10 end to be swung into position so as to place the part 14 on the base 10 of the rail and very close to the web 15. The slabs 5 are placed so that ends of the adjoining slabs having the downwardly extending portions 15 11 alternate along each of the rails and, consequently, when the slabs are pushed together edgewise along the track, the dove-tailing flanges 6 and 7 and the end portions 11 of the slabs will lock the pavement in position against any lifting movement. Edgewise movement of the slabs along the rails is prevented by any suitable means, such as by means of spikes.

In the form of construction shown, the end 25 slabs, that is, the slabs located at the edges of the cross pavement, are provided with downwardly sloping portions 18 that extend to the ties 2 and preferably terminate in laterally extending flanges 19. The edge slabs of 30 the pavement between the rails may be secured in position by means of rail spikes, such as the spikes 20 which will operate to secure the slabs in position and prevent their separation in a direction along the rails.

35 When it is desired to raise or adjust the rails, that is, when it is desired to repair the track, all that is required is to raise the spikes 20 and the slabs may be easily removed by separating them edgewise and lifting any 40 number of them away from the rails, the ends of alternate slabs along either one of the rails being removable by reason of the clearance between the downwardly inclined portions 14 that rest upon the base of the rail.

The rails, as is well known, are often used as parts of the circuits of railway signalling systems and other indicating and controlling devices and, where one rail is used as one part 50 of the circuit and the other rail is used as another part of the circuit, or is used as a part of another circuit, or system, it is necessary to maintain the rails electrically insulated one from the other. By my invention, 55 I have provided a means whereby the slabs may not only efficiently perform their function as parts of a removable cross-rail pavement, but also whereby the electrical insulation of the rails may be maintained. The 60 slabs are formed of a plurality of sections that are separated by insulating blocks. In the form of construction shown, suitably water-proofed or impregnated wooden blocks 65 25 are located between the parts 26 and 27 of each of the slabs 5. Both of the parts 26

and 27 have downwardly extending walls 28 and 29, respectively, and insulating blocks 25 are located between the walls 28 and 29 and rest upon the ties. In order to provide a cushioning area of insulating block which will cushion the strains and blows received by the slabs the insulating blocks preferably support the lower edges of the walls slightly above the ties. Bolts 30 extend through the blocks 25 and the walls 28, and the bolts 31 extend through the blocks 25 and the walls 29. The bolts 30, however, are so disposed as to be located in spaced and insulating relation with respect to the walls 29, and, consequently, with respect to the parts 27 of the slabs 5. The same is also true of the bolts 31, with respect to the walls 28 and the parts 26. The blocks 25 are so formed as to substantially fill the space between the walls 28 and 29, and the parts 26 and 27 having substantially equal length, the blocks 25 are located centrally along and midway between the rails 1 of the track. The blocks 25 thus form a continuous wall across the pavement and lengthwise of the slabs. They have a width substantially the same as that of the slabs 5, except that each block is provided with a tongue 34, having preferably inclined upper and lower edges 35, and each block is provided with a recess 36 that corresponds in shape to the tongue 34. The tongue 34 is located on one end of each block, and the recess 36 is located in the opposite edge of the block. This is true of the blocks intermediate the end blocks of the pavement. The end blocks have sloping edges, as at 38, that correspond to the inclined portions 18 of the slabs located at the edges of the pavement, and one of the end blocks is without a recess but is provided with a tongue, and the other of the end blocks is without a tongue and is provided with a recess. The lengths of the tongues, as measured in the direction that the rail 1 extends, is preferably the same as the width of the flange parts 6 and 7, so that when the slabs are separated and the flange parts 6 and 7 of contiguous slabs are clear of each other, the tongues 34 of the blocks will be likewise clear of the adjoining blocks. When, therefore, the slabs are pushed together, the flanges 6 and 7 will dove-tail with each other and the tongues 34 will likewise dove-tail with the portions of the blocks located on opposite sides of the recesses 36. Thus, the slabs will not only be interlocked with respect to each other, as described above, but also the blocks and the insulated material will be interlocked as well as interconnected with the parts or sections of the slabs. Furthermore, the sections of the slabs being interconnected by means of the insulating blocks 25, an elastic flexible element is introduced into the slab construction, which enables a cushioning support intermediate the rails and also prevents breaking, if an 130

exceptional load is placed on the pavement, since it enables a bending movement at the blocks in excess of that which would be permitted by the metal of the slabs and thus the life of the slabs is greatly increased.

5 I claim:

1. In a cross railroad pavement construction, a plurality of slabs extending between the webs of the rails, the ends of the slabs having downwardly extending portions that rest upon the bases of the rails, the slabs formed of a plurality of sections, blocks of electric insulating material located between the sections of each slab, and means for securing a block 10 to each section of a slab and for connecting the parts to each other through the blocks.
2. In a cross railroad pavement construction, a plurality of slabs extending between the webs of the rails, one end of each slab fitting the space beneath the top of the rail and the base of the rail, the opposite end of the slab having a part inclined downwardly towards the base of the rail to a point that will clear the top of the rail when the said end is 15 raised or lowered and while the opposite end is located intermediate the top and the base of the other rail, each slab formed of two sections, blocks located intermediate the sections of each slab, and means for securing 20 each section to the block, the means for securing each section to the block being separate and independent of the means for securing the block to the other of the sections of 25 the slab.
3. In a cross railroad pavement construction, a plurality of slabs extending between the webs of the rails, the opposite ends of the slab having parts resting on the bases of the rails, each slab formed of two sections, blocks 30 located intermediate the sections of each slab and supporting the inner ends of the sections, and means for securing each section to the block, the means for securing each section to the block being separate and independent of 35 the means for securing the other of the sections of the slab to the block, the slabs having short flange portions located along the edges of the slabs, the flanges of one slab dove-tailing with the flanges of the adjoining slab, 40 the blocks having tongues and recesses, each block having a tongue on one edge and a recess in the opposite edge, whereby the slabs will interlock and the blocks will interlock to prevent relative displacement.

55 In witness whereof I have hereunto signed my name to this specification.

HUBERT A. MYERS.
